WINDOW CONTROL MEANS

Laurence C. Maher, Asbury Park, N. J.

Application February 24, 1940, Serial No. 320,626

12 Claims. (Cl. 192—8)

The present invention relates to an improvement in devices for controlling sectional window ventilating devices for motor cars, although not so limited, and such modifications as may be made to permit of locking control of the manual raising or lowering of windows in automobile doors, and the like, whereby the sections or windows, so manually controlled, may be automatically locked in adjusted positions, against wind pressure, or other undesired forces, as the adjustments are made.

In some respects, the present invention is an improvement over the structures shown and described in my United States Patent No. 2,231,728 of February 11, 1941, and the present improvement comprehends the use of structures, as will hereinafter appear, in detail, whereby modified or added structures and functions are involved, to provide means which may be automatically resistant to normal reactions against closing action of the adjusted parts involved, after adjustment takes place to the desired ventilating or closing degree.

Amongst the features of advantage in the present improvement, is the provision of a mechanism, whereby in one use, means are provided for adjustably setting a pivoted, ventilating section of a window, whereby resistant locking of said section, for vehicle or other purposes, is automatically accomplished at the termination of said adjustment control in any desired position, or degree, without recourse to any added manipulation of extraneous parts.

A further advantage lies in the provision of a modified form of the structure herein, adaptable to the raising and lowering of vehicle windows, especially sliding glass window constructions, whereby, by the provision of a simple controlled, movable construction, such windows may be merely opened or closed to the desired degree of opening or closing, and, upon cessation of the adjusting operation, the movable control means automatically lock the movable or slideable window or sector in desired position. Thus, the manual control means contain inherent locking means for preventing inadvertent movement of the window itself or its sectors, by forces other than the manual movement control means, both of which are, preferably, controlled from the interior side of the window.

In certain constructions, herein disclosed, means for automatically braking the operative mechanisms are shown, whereby the operative means for ventilating or other purposes, are immediately operative to lock the said means in

open ventilating position, or closed, non-ventilating position, as desired.

The foregoing and other features of advantage, will appear as the herein description proceeds and it will be obvious that modifications may be made in the structure herein disclosed and described without departing from the spirit hereof or the scope of the appended claims.

In the drawings,

Fig. 1 is a fragmentary view, in elevation, showing the herein device in connection with a segmental, ventilating window control;

Fig. 2 is a sectional view, taken on line 2—2, Fig. 1, looking in the direction of the arrows;

Fig. 3 is a transverse sectional view taken on line 3—3, Fig. 2, looking in the direction of the arrows;

Fig. 4 is a side view of a modified form of the present construction, showing the device arranged for raising and lowering a sliding window;

Fig. 5 is an end view taken on line 5—5, Fig. 4, looking in the direction of the arrows;

Fig. 6 is a view, similar to Fig. 4, showing further operative details of Fig. 4;

Fig. 7 is a fragmentary sectional view, taken on line 7—7, Fig. 6, looking in the direction of the arrows;

Fig. 8 is a fragmentary view in side elevation showing a form of gear braking means in connection with the constructions shown in Figs. 4 and 6;

Fig. 9 is a view in elevation, showing a fragmentary, modified form of braking device; and

Fig. 10 is a sectional view, taken on line 10—10, Fig. 9, looking in the direction of the arrows, showing certain control and mechanism braking means therefor.

In the drawings, Fig. 1 discloses a vertically pivoted ventilating window section, generally denoted by S, which comprises a transparent glass pane 26, shown fragmentary, for convenience, which is surrounded by a supporting, encompassing metal frame 24, and a filler insert member 25, which is inserted between the edges of the pane 26 and the outer frame 24, in the usual manner.

The lower horizontal portion of the frame, Figs. 1 and 2, is provided with a fixed, offset pivot extension 23', the upper end of which is provided with a frame and pivot connecting flange 24'. The upper horizontal edge of the frame 24, not shown, is provided with a similar, aligned upper pivot, not shown, which fits into an external upper, outer door frame, whereby the glass panel 26 may be swung inwardly or outwardly, like a

rudder, for ventilating purposes. This type of structure is well known in current automobile doors.

As a means for operating to vertically swing the rudder-like pane 26 and its framing, there is provided a, preferably, metal support comprising an angle iron member composed of a lower flange 1, and an integral, vertical flange 2, Fig. 2, which may form the platform connection between the lower end of the opening of the window opening in the door frame, not shown, but understood, in this construction.

On the lower leg of the angle 1, of the angle 1-2, is rotatably located a compound gear 9, which is constructed with a rim portion 7, the upper face of which is provided with a circular rim of gear teeth 8, preferably, in the form of a bevel gear. This bevel gear is floating and rotatably rests upon the upper face 20 of the angle leg 1, Fig. 2, and being without a fixed rotational center, is, as thus mounted for free floating rotation thereon, without central or axial rotative constriction.

The vertical leg 2 of the angle iron near its upper edge 12, is provided with an open ended vertical trunnion bearing slot 22, which receives therein, as a constructional detail, the hub or boss 14' of the fixed center, bevel toothed pinion 14", the bevel teeth 14 of which engageably and rotatably mesh with the teeth 8 of the bevel gear 9, at an angle thereto.

In order to removably and replaceably hold the bevel pinion 14" in fixed rotative position in the slotted bearing 22, there is provided a reversely slotted keeper plate 12, which is forked over the hub 14' of pinion 14 and is fixedly held to the vertical leg 2 of the angle iron 1-2 by screws 13-13, which enter the leg 2, to hold said plate 12 to leg 2, Figs. 1 and 2, as at 12', Figs. 1 and 2.

The pinion 14" is provided with an affixed, frictionally held pinion rotating shaft 15, whereby the pinion 14" may be manually rotated, said shaft 15 having a reduced shoulder 19, and an extended portion upon the outer end of which is located a modified thumb nut 17, whereby, upon manual rotation of the nut 17, the pinion 14" is rotated on its fixed center to cause rotation of the floating gear 9. Rotation of pinion 14" causes consequent rotation of gear 9, and this movement, in turn, causes rotation of vertical shaft 23', which, as earlier herein indicated, is fixedly attached to the bottom of the outer window frame 24, by flange 24'. The lower end of pivot 23' is connected to a bridging bar 23, Figs. 2 and 3, which is rigidly attached at its opposite ends to the circular rim 7, which is integral with gear blank 7, Figs. 2 and 3. Thus rotation of gear 9 causes a rotational or pivotal movement of frame 24 and its attached window panel 26.

As a means for maintaining the offset moving or floating gear 9 in desired operative position upon its angle base 1, the inner lower face on rim 7, is provided with a fixed tooth gear section 10, Figs. 1 and 2, which is meshed with a toothed pinion 3, which has an integral stub shaft 4, which in turn, is mounted for a fixed central rotation in angle flange 1, and there held by a pinned on collar 5, by pin 6 through shaft 4. Rotation of thumb nut 17, causes bevel pinion 14" to rotate floating gear 9, to rotate glass panel 26, said gear 9 being held in oscillating floating rotational position by spur pinion 3. Upon cessation of the rotation of thumb nut 17, any extraneous

air or pressure movements upon the pivoted panel 5, or 26, moving the panel through the angle α , tends to shuck or cause offset of gear 9 out of its normal driven position with spur pinion 3, in the dotted lines as indicated by b, Fig. 3, shown diagrammatically, and thus cramp gear 9 against pinion 3, and thus act as a lock for gear 9, against any further movement, except as controlled by manipulation by thumb nut 17 and its controlled bevel pinion 14". Thus any extraneous or reverse force applied to panel 5, or 26, causes a rigid lock of the said panel, unless readjusted or released by applied movement through manipulation of pinion 14".

The modified device, of Figs. 4 and 5, while mounted on an angle member 1-2, as described for Figs. 1, 2 and 3, may be without bevel teeth 8 on gear 9, and thus, its outer periphery 25, being smooth, is in substantial, more or less frictional contact with the inner face 2' of leg 2 of the angle iron 1-2. In this construction the leg 1 of the angle iron may be vertically arranged, while the leg 2 is horizontally located and the bridge plate 23 has fixedly mounted thereon the shaft 23' and the gear 9 is thus floatingly mounted for vertical rotation in its operative position. The horizontal leg 2 of the angle iron 1-2 may be provided with two right angled retaining ledges 22', which may overlap the outer face 7' of the gear 9, thus to retain the gear 9 in free floating position upon the inner face of leg 1 of the angle iron, as shown in Fig. 5.

The invention according to Figs. 4 and 5 may be employed to raise or lower a window sash, attached to arm f by any known means. The pinion 3 may be rotated by means of a handle mounted on shaft 4. By clockwise rotation of the pinion 3, the floating gear 9 is rotated substantially about the axis of shaft 23' to effect raising of the sash. The weight of the sash tends to rock the gear about an axis between the pinion 3 and angle face 2', thereby jamming the gear 9 against further rotation about this last mentioned axis. By rotating the pinion 3 in the reverse direction the gear 9 is loosened and made to rotate substantially about its own axis.

In the modified constructions shown in Figs. 4, 5, 6, 7 and 8, the gear 9 is thus located in vertical rotative position whereby these latter modified forms may be utilized for raising and lowering window panels and their appurtenant frames, as will now be described.

As shown in Figs. 4 and 5, the integral bridge piece 23 may be suitably affixed near one face of the gear 9, and there may be attached thereto an offset, extending window elevating control lever C, shown in fragmented extension, in Figs. 4 and 5, whereby, upon operation of pinion 3, gear 9 is rotated and the lower end f of lever C may be oscillated in the direction of arrows d-e, Fig. 4 to raise or lower the vertically movable section of a window. When the window moving section is raised, or lowered, the natural load or weight reaction thereof, causes the gear 9 to oscillate about the center of the fixed center actuating pinion 3, and thus, by frictional offset, rim engagement with the inner surface 2' of leg 2, to jam, and thus prevent any rotational movement of gear 9, until the pinion 3 is further moved, as desired. Thus pinion 3 binds the window operating gear and arm in locked position.

The offset movement of gear 9 is shown in exaggerated form by the dotted section b, Fig. 3, this offset movement causing a wedging action of

gear 9, between the fixed pinion 3 and one face of the angle iron leg 1-2, which action is releasable by manual operation of pinion 3, in either rotational direction.

In Figs. 6 and 7 there is disclosed a modified means for maintaining the gear 9 of Figs. 4 and 5 in operative floating position, for oscillating jam or lock operation, and in which views, the angle iron legs 1 and 2 are shown, as previously described, the gear 9, in the present instance being provided with a circumferential retaining groove G in its perimeter 25, into which groove G is mounted two opposed gib-like lugs D, which are held to leg 1, by screws S-S, or equivalent means.

The said guiding lugs D-D are so located as to be engageable below the rotatable center of internal gear 9, Fig. 6, to permit of free movement of said gear about its variable rotational center. The fixed center pinion 3, as previously described, engages the internal gear teeth 10 of gear 9, and upon rotation of pinion 3 upon its fixed central shaft 4, Fig. 6, the gear 9 is caused to rotate. Fig. 7 shows one form of the groove and tongue gear holding means, in partial section.

In Fig. 8 there is disclosed a fragmentary, sectional view, the structure of which, in its details may be applied to a structure, modified from Figs. 4 or 6. In this structure, the angle iron 1-2, is utilized, as earlier described, but the floating gear 9, which is also provided with internal gear teeth 10, to cooperate with the teeth 11 of fixed pinion 3 of, for instance, Figs. 3, 4 or 6, is located in such a manner that its perimeter 25 is spaced a predetermined distance from the inner face 2' of leg 2 of the angle iron 1-2, so as to permit of the introduction of a pivoted brake shoe S', which is pivoted to leg 1, by a pivot pin P. The brake shoe S' may be crescent shaped, with its operative braking face P' so located as to be adjustably engageable with the face 25 of gear 9, so that when said gear is moved off its non-fixed center, as shown at b, Fig. 8, it will engage with the braking face P' when in offset position and be jammed against any rotational movement, except as controlled rotation by the control pinion 3.

In Figs. 9 and 10, are shown further modified forms of the load locking or braking means, wherein the main, non-fixed, rotational gear 41, of free floating habit, as described for gear 9, of Figs. 1 to 7 inclusive, is controlled by an external toothed spur pinion 36, Fig. 9, the fixed shaft 37 of which, when manually turned, causes the fixed center spur pinion 36 to rotate the floating gear 41, in either of the opposed directions of the arrows 46-46, Fig. 9, as shown in connection with the window lifting lever 45. As in the previously described figures, the gear 41 is not mounted to rotate about a fixed center, yet the teeth 40 thereof are engageable with the teeth 39 of spur pinions 36. The toothed portion 40 of gear 41 may be of sufficient circumferential amplitude to permit the said gear 41 to be rotated in a complete revolution, or as shown in Fig. 9, in any lesser degree thereof.

The gear 41 may have a bridge piece 42 attached to one face thereof, and suitably held thereto by suitable terminal rivets 43-43 and spaced from the gear by spacer blocks 42'. The mid-portion of the bridge piece 42 may have rigidly affixed thereto by rivets 44, one end of a window lifting lever arm 45, so that rotative and load reaction forces may be transmitted by and to gear 41 by said arm 45.

The floating lock or jam movement allotted to gear 41 is indicated by the dotted lines 46', Fig. 9.

The manually operated pinion is rotatably held between two frame forming plates 35 and 38, shown fragmentarily in Figs. 9 and 10, and these may be suitably affixed to appurtenant portions of the window frame or holding structure, not shown, to accomplish the desired purpose.

10 The frame portion 38, in the form of a strip, Fig. 9, may be bored to rotatably support the pinion operating shaft 37, Fig. 9, and its lower end may be extended to pivotally support thereon, a preferably, hollow, flanged brake shoe 47,

15 said shoe being held thereto by a headed pivot 39, Figs. 9 and 10. The brake shoe 47 is intended to have some pivotal freedom on its mounting, and is so mounted, as shown in Fig. 10 to flangedly span both faces of gear 41, with its hollow,

20 interior chamber 48 located opposite the inner non-toothed face of the ring or annular formed gear 41. As thus shown, the gear 41, while rotatably controlled by the pinion 36 in either direction of rotation, as per arrows 46-46, is free to

25 be offset, upon the brake shoe support 47 by a static load imposed thereon, by the weight of the window structure controlled by the lever 45. One direction of such offset is shown by the dotted construction lines 46', Fig. 9. Such offset movement of the gear 41 may be in the opposite oscillatory direction from that indicated in Fig. 9.

The interior chamber 48 may be provided with a flat or leaf spring 49, which may be of arcuate construction, as shown dotted, in Fig. 9, so that while its outer extremities may bear upon the lower face of the brake shoe chamber 48, the upper crown thereof may bear upon the inner face of the annular gear 41, Figs. 9 and 10. This spring, as constructed, acts normally to prevent rattle and looseness of the coacting parts, but does not interfere with the double, offset locking action between the gear 41 and the locking brake shoe 47, such double offset action being caused by the mutual movements of the brake shoe and the gear 41.

In each of the constructions herein disclosed, it is obvious that the floating main gear is manually controlled for rotational movement by a 50 fixed center pinion in desired window adjustment control, and, upon release of the pinion control movement the floating gear means, by reason of the secondary or adjunctive window load imposed thereon, is caused to move to an offset 55 jamming or load braking position, immediately, without undue looseness or chatter, but is also immediately restorable and movable to operative position upon operation of the manually operable pinion.

60 The last above noted functional action is common to all of the structural forms shown herein.

What is claimed is:

1. In combination, an angle iron base comprising a horizontal web provided with a hole near its axis, and an upright web having a bearing opening in its upper portion; a drive miter-pinion mounted in said bearing opening; a floating annular gear resting on said horizontal web and having miter-gear teeth engaging said pinion; said gear having an inner circumferential face; a braking fulcrum part mounted in said hole, said part substantially opposing said pinion; transmitting means driven by the gear at a point remote from said fulcrum part; said gear, pinion, transmitting means, and said fulcrum

part being so disposed relative to each other that extraneous force on said transmitting means causes the said fulcrum part to be pressed upon by said circumferential face with a force approximately normal to the fulcrum part and causes the gear teeth to press upon the drive member with a force substantially normal to the path of the teeth of the drive member; the direction of drive of said drive member being substantially tangential to said gear.

2. In combination, an angle iron base comprising a horizontal web provided with a bearing hole, and an upright web provided with a bearing opening; a backing spur pinion flat on the lower web and having integral therewith a stub-shaft rotatable in said bearing hole; a floating annular gear resting on said lower web and having internal gear teeth meshing with the pinion at the side adjacent to the upright web; said gear having outwardly downwardly inclined crown miter gear teeth at its upper part; a drive shaft in said opening; a drive miter pinion mounted on said shaft; the teeth of the miter pinion converging toward the axis of the gear, and meshing from above with the miter crown teeth, whereby the annular gear is held flat upon the lower web and in mesh with both pinions; whereby any torque applied directly to said gear causes the floating gear to rock on a changeable vertical axis thereby causing the miter teeth of the annular gear and the teeth of the miter pinion to press together and wedge that part of the annular gear between the lower web and the teeth of the miter gear, and causing the spur pinion and annular gear to press together; thereby causing all of the engaged teeth to jam, thereby holding the gear against rotation by torque applied directly thereto.

3. In combination, a pivoted braking member provided with opposed side flanges; a floating gear provided with external teeth and having the inner circumferential portion thereof loosely engaging said member between said flanges; an arm adapted to move a window sash and mounted on said gear; a drive pinion engaging said teeth and mounted to impart movement to the gear; the braking member and the pinion being positioned to hold the floating gear in engagement with the member and the pinion; whereby an extraneous force on said arm tending to rock said gear on a point between the pinion and the member causes the gear to jam on the member.

4. In combination, an angle iron base comprising a horizontal web having a bearing portion near its axis, and an upright web having a recess in its upper portion; a backing spur pinion flat on the lower web and having integral therewith a stub-shaft rotatable in said bearing opening and having a collar fast on its lower end and engaging against the lower face of the lower web to hold said pinion in place; a floating annular gear or rack resting on said lower web and having an internal diameter nearly twice as great as the diameter of the pinion, and having internal gear teeth meshing with the pinion at the side adjacent to the upright web; said gear having outwardly downwardly inclined crown miter-gear teeth at its upper part and having a diametric bar across the gear carrying a spindle coaxial with the gear supporting the frame of a glass of a ventilating window; a bearing plate removably secured over said recess in the upright web and provided with a large bearing opening; a drive miter-pinion having a large axially bored bearing hub rotatable in said large opening and

removable upwardly through the recess when the bearing plate is removed; an actuating handle for driving said drive pinion having a short shaft engaged with a friction fit or other driving relation in the bore of the hub; a washer on the hub engaged between the upright web and the miter pinion; the teeth of the miter pinion converging toward the axis of the gear, and meshing from above with the miter crown teeth, whereby the

10 annular gear is held flat upon the lower web and in mesh with both pinions; whereby the annular gear is held in place only by the lower web and the two pinions, whereby any torque applied directly to said spindle causes the floating annular gear to rock on a somewhat changeable vertical axis of oscillation near the plane of the axes of the pinions and between the miter pinion and the axis of the spur pinion; thereby causing the miter gear on the side of said plane toward which the torque is directed to press together and wedge that part of the annular gear between the lower web and the teeth of the miter gear, and causing the spur gear teeth at the opposite side of said plane to press together therewith, thereby causing all of the engaged teeth to jam, thereby holding the spindle against rotation by torque applied directly thereto.

5. In combination, an angle iron base comprising a horizontal web having an upright retaining ledge and an upright web provided with a bearing opening; a floating annular gear having the periphery thereof disposed against said horizontal web and a side face disposed against said upright web, and provided with internal gear teeth; said gear being provided with a diametric bar across the gear; a stud mounted on said bar; a crank lever attached to said stud and adapted to move a window sash; a drive shaft engaged in said bearing opening; a drive pinion mounted on said drive shaft and provided with teeth meshing with said gear and holding the gear against said horizontal web; whereby the annular gear is held in place only by the horizontal web, the upright ledge thereof, and the pinion, whereby any torque applied directly to said stud causes the floating annular gear to rock on a somewhat changeable horizontal axis between the axis of the stud and the horizontal web; thereby causing said annular gear to be forced frictionally against the horizontal web and causing gear and pinion teeth to jam when a torque is applied to the gear by said lever, thereby holding the drive pinion and shaft against rotation actuated by said gear.

6. In combination, a frame strip adapted to be affixed to appurtenant parts of a window frame and provided with a pivot hole and a bearing opening; a pin in said hole; a drive shaft in said opening; a pinion on said shaft; a washer spacing said pinion from the face of said strip a frame plate disposed against the outer face of said pinion and held in spaced relation to said strip; a floating annular gear provided with external teeth and having the peripheral portion thereof meshing said pinion and received between said strip and said plate; an internal brake shoe adapted to engage the inner annular face of said gear and provided with flanges adapted to engage both side faces of the gear; said shoe being provided with a pivot hole and being pivoted to said strip by said pin; diametrically opposed spacing blocks mounted on the face of said gear opposite said frame strip; a diametric bar across said gear mounted on said blocks an arm mounted on said bar and adapted to move a window, whereby the annular gear is held in place only by the drive

pinion, the frame strip, the frame plate and the brake shoe, whereby any torque applied directly to the diametric bar causes the floating gear to rock on a somewhat changeable axis near the brake shoe; thereby causing said gear to be forced frictionally against said shoe and causing gear and pinion teeth to jam when a force is applied directly to the arm.

7. In combination a fulcrum member; a floating circular gear member provided with an axial shaft and having inner and outer peripheral portions, said fulcrum member loosely engaging one of said peripheral portions; and gear drive means engaging the other of said peripheral portions substantially opposite said fulcrum member for rotating said arcuate member and shaft about their common axis, and permitting said gear member to rock only slightly about an axis substantially between a set of points on the arcuate member engaging the fulcrum member and a set of points engaging the drive means, the distance between said sets of points being less than the distance from the shaft to either of said sets of points, whereby when a torque is applied to the shaft the gear member is not constrained to rotate about said common axis but rotates about the second mentioned axis until stopped by the fulcrum member and the drive means said fulcrum member being a pinion.

8. In combination a fulcrum member; a floating arcuate gear member provided with an axial shaft and having inner and outer peripheral portions, said fulcrum member loosely engaging one of said peripheral portions; and gear drive means engaging the other of said peripheral portions substantially opposite said fulcrum member for rotating said arcuate member and shaft about their common axis and for allowing said arcuate member to rock slightly about an axis substantially between points on the arcuate member engaging the fulcrum member and points engaging the drive means, whereby when a torque is applied to said shaft the gear member will slightly rotate about the last mentioned axis and be held against further movement by said means and member, said fulcrum member engaging the inner peripheral portion of the gear member.

9. In combination a floating arcuate gear having inwardly facing and outer substantially coaxial peripheries of approximately the same radius; a fulcrum part engaged against one of said peripheries; said gear having gear teeth adjacent to the other periphery; a drive pinion engaged with said teeth near and in opposition to said fulcrum part, an adjacent portion of the gear lying between the pinion teeth and said fulcrum

part; said gear, teeth, pinion and part being so disposed relative to each other that torque applied to the gear causes the gear to rock on a changeable axis approximately between the fulcrum part and pinion teeth, thereby causing said annular gear to be forced against said fulcrum and said gear and pinion teeth to jam.

10. In combination a floating annular gear having inner and outer peripheries; a fulcrum part engaged against one of said peripheries; said gear having gear teeth adjacent to the other periphery; a drive pinion engaged with said teeth near and in opposition to said fulcrum part; and transmitting means driven by the gear.

11. In combination a supporting member having a bearing opening; a floating annular gear having inner and outer peripheries of approximately the same diameter; a fulcrum part carried by said supporting member and engaged against one of said peripheries; said gear having gear teeth adjacent to the other periphery; a drive shaft in said opening; a drive pinion carried by the shaft and engaged with said teeth near and in opposition to said fulcrum part and on the same side of the gear axis as said fulcrum part; whereby an adjacent portion of the gear annulus lies between the pinion teeth and said fulcrum part; and transmitting means driven by the gear at a point remote from said fulcrum part; said means, gear, teeth, pinion and part being so disposed relative to each other that extraneous force on the transmitting means applying torque to the gear causes the gear to rock on a slightly changeable axis, between the fulcrum part and pinion teeth, thereby causing said annular gear to be forced against said fulcrum, causing the gear and pinion teeth to jam, thereby holding the drive pinion and shaft against rotation by said gear.

12. In combination a supporting member having a flat face and a bearing opening; a floating annular gear disposed flat against said face and having inner and outer peripheries of approximately the same diameter; a fulcrum part carried by said supporting member and engaged against one of said peripheries; said gear having gear teeth adjacent to the other peripheries; a drive shaft in said opening; a pinion carried by the shaft and engaged with said teeth near and in opposition to said fulcrum part and on the same side of the gear axis as said fulcrum part, whereby an adjacent portion of the gear lies between the pinion teeth and said fulcrum part; and transmitting means driven by the gear at a point remote from said fulcrum part.

LAURENCE C. MAHER.
